CLAIM

We claim the ornamental design for a wireless charger, as
shown and described.

DESCRIPTION

FIG. 1 is a top perspective view of a wireless charger in a
first charging configuration where panels of the wireless
charger are folded into a triangular shape.

FIG. 2 is a front view of the wireless charger in the first
charging configuration.

FIG. 3 is a back view of the wireless charger in the first
charging configuration.

FIG. 4 left side view of the wireless charger in the first
charging configuration.

FIG. 5 is a right view of the wireless charger in the first
charging configuration.

FIG. 6 is a top view of the wireless charger in the first
charging configuration.

FIG. 7 is a bottom view of the wireless charger in the first
charging configuration.

FIG. 8 is a bottom perspective view of the wireless charger
in the triangular charging configuration.

FIG. 9 is a top perspective view of the wireless charger in a
second charging configuration where the wireless charger is
unfolded such that the panels are aligned in a plane.

FIG. 10 is a front side view of the wireless charger in the
second charging configuration.

FIG. 11 is a back side view of the wireless charger in the
second charging configuration.

FIG. 12 a right side view of the wireless charger in the
second charging configuration.

FIG. 13 is a left side view of the wireless charger in the
second charging configuration.

FIG. 14 is a top view of the wireless charger in the second
charging configuration.

FIG. 15 is a bottom view of the wireless charger in the
second charging configuration.

FIG. 16 is a bottom perspective view of the wireless charger
in the second charging configuration.

FIG. 17 is a perspective view of the wireless charger in a
third charging configuration where the wireless charger is
folded with the panels forming a single stack.

FIG. 18 is a left side view of the wireless charger in the third
charging configuration.

FIG. 19 is a right side view of the wireless charger in the
third charging configuration.

FIG. 20 is a front side view of the wireless charger in the
third charging configuration.

FIG. 21 is a back side view of the wireless charger in the
third charging configuration.

FIG. 22 is a top view of the wireless charger in the third
charging configuration.

(Continued)

FIG. 23 is a bottom view of the wireless charger in the third charging configuration; and,
 FIG. 24 is a bottom perspective view of the wireless charger in the third charging configuration.
 The broken lines shown in FIGS. 1-24 are for the purpose of illustrating portions of the wireless charging device that form no part of the claimed design.
